UNITED STATES PATENT OFFICE.

MARY CONNOR, OF HOLYOKE, MASSACHUSETTS

CHILD'S HARNESS.

Application filed January 10, 1921. Serial No. 436,387.

To all whom it may concern:

Be it known that MARY CONNOR, a citizen of the Dominion of Canada, residing at Holyoke, in the county of Hampden and State of Massachusetts, has invented certain new and useful Improvements in Children's Harness, of which the following is a specification.

This invention relates to improvements in harness for restraining children from assuming standing or upright positions in beds or cribs and consists in means for attaching an outer garment of a child to a bed or crib so as to permit of a free turning 10 action of the child in the crib or bed and to restrain it from assuming an upright position. 15

With the above and other objects in view this invention relates to certain new and useful constructions, combinations and arrangements of parts, clearly described in the following specification and fully illustrated in the accompanying drawings, in which :

Fig. 1 is a perspective view showing the
25 device applied to a crib.

Fig. 2 is a detail view, partly in showing a hook of a modified form.

Referring to the accompanying drawings
5 designates a crib which supports the mat-

30 tress 6 on which the child A is supported.
The child is provided with a nightgown or

outer garment 7 to the front wall of which the loop 8 is connected and to the back wall of which the loop 9 is connected. A restraining cord or strap or the like 10 is connected with one corner of the crib and a similar strap or cord 11 is connected with the opposite corner of the crib. The straps 10 and 11 are each provided with a connecting device which is shown to be in the form of a loop 12 which can be opened and closed by means of a snap button 13 and which is adapted to embrace one of the corner posts of the crib as will be readily understood. The straps 10 and 11 are connected with each other at 14 and are extended therefrom to provide connecting straps 15 and 16 which are adapted to be extended through the loops 8 and 9 and then connected to each

50 other. In place of the snap button 13 and the loop 12 I may employ a hook 17 having

an eye 17^a whereby it may be detachably connected with either of the straps 10 and 11.

A strap 20 is extended across the breast of the child, one end of which is connected to one side of the mattress or crib and the other end of which is connected to the opposite side of the mattress or crib. This strap is the full equivalent for this purpose of the usual upper sheet, when the same is properly pinned in position as a covering for the child. The foot straps prevent the child from shifting longitudinally out of the bed covering while the transverse strap or bed covering restrain the child against moving to upright position. 55 60 65

The harness permits of a child to roll in the bed or crib freely and does not bind the child or cause chafing and should the child attempt to assume an upright or standing position he or she will be effectively prevented by the action of the restraining device upon the nightgown or garment worn. 70

The device can be readily attached to any nightgown and permits of the proper positioning of the bed clothes over the child so that the child can be protected and prevented from displacing the bed clothes from protecting position. 75

My invention has been successfully tried out with a large number of children and has been a source of great comfort and security. 80

Having described my invention, I claim:

A child's harness consisting of a combination with a night gown adapted to reach to the feet of the infant wearer, two diverging straps adapted to be detachably connected with the strap on one end of a crib or the like and flexible retaining straps connected to the front and back walls of the night gown, between the feet of the wearer and at a point near said feet and connected to the detachable straps, to maintain the infant in a position in the bed and to restrain him against movement lengthwise in the bed away from said end legs, means being provided for restraining the infant in a reclining position in the bed consisting of a flexible member traversing the infant and secured to the sides of the bed or crib. 100

Signed by me at Holyoke, Massachusetts.
MARY CONNOR.
